UNITED STATES PATENT OFFICE.

WILLIAM SCHMIDT AND ATTIE FILIPPONI, OF TRENTON, NEW JERSEY.

HEADLIGHT-DEFLECTOR.

1,265,258.

Specification of Letters Patent.

Patented May 7, 1918.

Application filed May 25, 1917. Serial No. 171,040.

To all whom it may concern:

Be it known that we, WILLIAM SCHMIDT and ATTIE FILIPPONI, citizens of the United States, residing at Trenton, in the county of Mercer, State of New Jersey, have invented certain new and useful Improvements in Headlight-Deflectors; and we do hereby declare the following to be a full, clear, and exact description of the invention, such as will enable others skilled in the art to which it appertains to make and use the same.

This invention relates to improvements in headlights and particularly to dimming devices therefor.

One object of the present invention is to provide a device of this character whereby the light from the lamps will be effectively shielded from the eyes of the pedestrians and other drivers, but by means of which the light will be projected onto the ground with the full intensity.

Another object is to provide a device of this character which is capable of ready use on lamps now in use.

Other objects and advantages will be apparent from the following description when taken in connection with the accompanying drawing.

In the drawing:

Figure 1 is a front elevation of a headlight equipped with my improved dimming device.

Fig. 2 is a vertical central sectional view through the headlight.

Referring particularly to the accompany-

ing drawing 10 represents the frame of the front of the headlight, in which is secured the usual disk of clear glass 11. Secured at their ends to the said frame and extending transversely of the lamp, in rear of the glass 11, are a plurality of brown or other dark-colored glass slats or strips 12, the rear longer edges of said slats being disposed at higher levels than the front longer edges, and said front edges being disposed below the horizontal planes of the rear edges, whereby the light from the lamp will be deflected on the rear faces of the slats downwardly toward the ground. By this arrangement no direct light from the interior of the lamp can be seen from the front, thereby protecting the eyes of pedestrians and drivers of other vehicles from the usual blinding glare which emanates from the headlights.

What is claimed is:

A deflecting device for an automobile headlight including a frame, a glass disk mounted in the frame and being clear and transparent, and a plurality of stationary transversely arranged jalousied dark-colored translucent glass slats secured to the said frame and in rear of the glass disk.

In testimony whereof, we affix our signatures in the presence of two witnesses.

WILLIAM SCHMIDT.
ATTIE FILIPPONI.
